UNITED STATES PATENT OFFICE.

CHARLES HENRI LINDECKER, OF BRIANCON, FRANCE.

SUSPENSION MEMBER FOR SIX-WHEEL VEHICLES.

No. 838,348.

Specification of Letters Patent.

Patented Dec. 11, 1906.

Application filed October 18, 1905. Serial No. 283,390.

To all whom it may concern:

Be it known that I, CHARLES HENRI LINDECKER, captain, a citizen of the Republic of France, residing at Briancon, Villa 5 Yvette, Hautes-Alpes department, in the Republic of France, have invented certain new and useful Improvements in the Suspension Members for Six-Wheel Vehicles, of which the following is a specification.

This invention relates to a system of suspension for six-wheel vehicles; and it has for its object to so construct a system of this character that all the wheels will be always on the ground, however uneven the surface of the road may be, and that the load will always be portioned out among the axles in the same manner.

Two embodiments of this invention are shown diagrammatically in the accompanying drawings, in which—

Figure 1 is a longitudinal elevation of a vehicle. Figs. 2 and 3 are corresponding views, the middle wheels being shown as passing over a depression in Fig. 2 and over 25 a protuberance in Fig. 3. Fig. 4 shows in elevation a modified form of the device represented in the previous figures, but which is based on the same principle.

In the said device the frame 2 is carried by 30 the middle axle 1 and the springs 3 of the front and rear axles by means of the balance-levers 4. The said levers are connected to the middle axle by one of their ends to the springs 3 of the front and rear axles by their 35 other end and to the frame by their axis or central pivot. The frame is carried directly by the outer end of the springs 3 of the front and rear axles. Springs 5 (see Figs. 1 to 3) are interposed between the levers 4 and the frame to operate in the same manner as the flat springs now in use, and which are mounted on the middle axle.

The levers 4 may be pivoted to the middle axle, in which case the frame may bear upon 45 the said levers through the medium of the links 6. The said levers may as an alternative be connected to the middle axle by a system of suitable slideways, or they may be suspended to the same by means of shackles. 50 In the two latter cases their axis or pivot may be secured directly to the springs 5 without the intervention of links.

The springs 5 may be flat springs secured 55 to the frame by their middle, as shown by way of example in Figs. 1 to 3. A single spring is thus sufficient for the two levers 4

at the same side of the vehicle, or each lever may have its own spring, and the said spring may be spiral in the form of superposed shells or of any other suitable shape. The 60 said springs may be interposed either between the levers and the frame or between the levers and the middle axle.

The middle axle of the vehicle is guided either by a slideway suitably braced, provided in a guide-plate or by a pushing-link pivoted to the frame at a suitable point, Fig. 4, or by any other suitable means. When the springs of the front and rear axles support the frame by means of shackles, it may 70 also be useful to guide the said front and rear axles in the same manner as the middle axle. This guiding of the axles is for the purpose, first, of transmitting directly the movement of translation between the frame 75 and the axles without the shackles having to act in this respect, the said shackles then only serving to allow of the relative movements between the different parts of the suspension taking place, and, secondly, of 80 keeping the axles in the proper relative position which may be rendered necessary by the transmission of the propulsion and the steering motion.

In the modified form shown in Fig. 4 the 85 balance-levers 4 operate both as balance-levers and as springs in place of those, 5, in the previous embodiment. All that need be done is to form the said levers 4 of flat springs which support the frame by their middle. 90

In the accompanying drawings there are shown, by way of example, different modes of connecting together the parts of the suspension.

In Figs. 1, 2, and 3, which show a device 95 having rigid levers, the levers 4 are pivoted to the middle axle 1 and to the shorter links 6, and flat springs 5 are interposed between them and the frame. The springs 3 at either end of the vehicle carry the frame by 100 means of the shackles 7, and all the axles are suitably guided by the slideways 8.

In Fig. 4, on the contrary, the flat springs 4', which operate as balance-levers, are pivoted directly to the frame by their middle, 105 and their end bears on the middle axle. The end springs 3 are pivoted directly to the ends of the frame, and the middle axle is guided by means of pusher-links 9.

The system of suspension shown and described fulfills the required purpose. The inclination of the balance-levers enables the

middle axle to take a different level from that of the front and rear axles, and this difference of level may take place at each side of the vehicle. When a middle wheel moves up with respect to the frame, the corresponding front and rear wheels move down, and vice versa. If the lever-arms are equal, the stroke of the middle axle is double that of the front and rear axles, and is made in a reverse direction, so that the change of level is the sum of these two movements.

On account of the symmetry of the movements with respect to the median plane the distances which separate the frame from each of the bearing-points of the front and rear wheels on the ground increase or decrease simultaneously to the same extent. The result is that it is the difference of level of the said bearing-points which determines the inclination of the frame without the level of the middle wheels having to intervene. The variations of the said inclination due to the accidental changes of level of the road are therefore only one-half of those to which the frame of a four-wheel vehicle would be subjected if the distance between the front and rear wheels of the said four-wheel vehicle was equal to the distance between the middle axle and the end axles of the six-wheel vehicle. The load will always remain portioned out in the same manner between the three axles, whatever may be the relative levels of the middle and end wheels, as this portioning out only depends on the length of the arms of the balance-levers and the said length remains very much the same. Abnormal, sudden, and accidental strains are thus avoided for the frame, the springs, the axles, and the wheels, strains which would require a much stronger construction for these members. On the other hand, the adherence of the driving and steering wheels is permanent whatever may be the place occupied by the vehicle. Fur-

thermore, the portioning out of the load and consequently the said adherence may be varied by giving suitable relative lengths to the arms of the balance-levers.

I claim—

1. A six-wheel car or vehicle comprising an underframe or chassis, three axles, rock rods or links the swinging axes of which are connected to the chassis, flat springs resting on the end axles, the outer ends of the said springs being connected to the chassis and their inner ends being connected to the outer ends of the rock-rods, the inner ends of the rock-rods being connected direct to the middle axle, whereby the said rock-rods are caused to swing simultaneously in opposite directions.

2. A six-wheel car or vehicle comprising an underframe or chassis, three axles, rock rods or links the swinging axes of which are connected to the chassis, flat springs resting on the end axles, the outer ends of the said springs being connected to the chassis and their inner ends being connected to the outer ends of the rock-rods, the rock-rods having their inner ends connected direct to the middle axle.

3. A six-wheel car or vehicle comprising an underframe or chassis, three axles, rock rods or links the swinging axes of which are connected to the chassis, flat springs resting on the end axles, the outer ends of the said springs being connected to the chassis and their inner ends being connected to the outer ends of the rock-rods, the inner ends of the rock-rods being connected directly to the middle axle.

In testimony that I claim the foregoing as my invention I have signed my name in presence of two subscribing witnesses.

CHARLES HENRI LINDECKER.
